UNITED STATES PATENT OFFICE

2,291,288

APPARATUS FOR DISPENSING GAS

Harry B. Rudd, Flushing, N. Y., assignor, by
mesne assignments, to Air Reduction Company,
Incorporated, a corporation of New York

Application August 10, 1939, Serial No. 289,389

2 Claims. (CL. 62—1)

My invention relates to the art of dispensing gas under pressure and, more particularly, to the art of charging or filling containers or drums with gas to a desired pressure.

In accordance with my invention, drums are charged in succession from a container holding gas at high pressure, an arrangement being provided for increasing the gas pressure within said container when desirable or necessary, as by the admission of liquefied gas thereinto.

Various other objects, advantages and features of my invention will become apparent from the following detailed description.

My invention resides in the art of filling drums, features and arrangements of the character 15 hereinabove described and claimed.

For an understanding of my invention and for an illustration of one of the forms thereof, reference is to be had to the accompanying drawing, in which:

Figure 1 is a diagrammatic representation showing my novel method of filling drums with gas; and

Fig. 2 is an enlarged plan view of one of the converters shown in Fig. 1.

Referring to the drawing, I have illustrated a container, casing or converter A which, as herein shown, is of seamless, tubular configuration and is supported in vertical upright relation by suitable standards 1 which rest upon a floor or other surface and, at their upper ends, are suitably attached to said converter A. As clearly shown, the converter A comprises a curved lower section 2 which, if desired, may terminate in a depending neck 3 having a passage threaded internally for the reception of a suitable closure device such, for example, as a nozzle 4, the upper threaded end of which is received in said internally threaded passage and the lower threaded end of which carries a cap 5 which may be removed when it becomes desirable to vent the converter A at the bottom thereof.

The converter A comprises a top wall 6 formed integrally therewith, this top wall 6, preferably, having greater thickness than the lower tubular wall and, in the example shown, said top wall 6 comprises a filling opening 7 of generally elliptical configuration. The opening 7 is adapted to be closed by a closure plate or member 8, the upper surface of which preferably carries a handle 9 and an attached chain 10. The closure plate 8 comprises an upstanding flange 11 and a laterally extending section 12 both of elliptical configuration in correspondence with the configuration of the filling opening 7. The corner

formed by the flange 11 and the laterally extending section 12 of the plate 8 is adapted to receive a gasket 13 which, when the converter A is used as hereinafter described, should be of suitable non-inflammable material such, for example, as wet asbestos. In Fig. 1, the closure plate 8 is shown in closing position, the gasket 13 being compressed between the closure plate section 12 and the adjacent lower surface of the top wall 6, these surfaces with which the gasket 13 coacts having previously been machined so as to render them smooth and even to thereby positively prevent leakage at the sealed joint.

A thin plate or member 14 formed preferably from metal having a thickness of $\frac{1}{16}$ of an inch, more or less, is positioned horizontally in the lower converter section and welded thereto so as to be suitably maintained in fixed position. The plate 14 should be provided with a plurality of holes or passages 14a.

As herein disclosed, the converter A is a duplicate, or substantially so, of the converter disclosed in my application filed of even date herewith, Serial No. 289,387, filed August 10, 1939.

Assuming that the closure plate 8 of the herein disclosed converter A is removed from its seat, a suitable quantity of liquefied gas, such as liquid oxygen, liquid air or liquid nitrogen, may be introduced into said converter, for example, in the manner disclosed in my aforesaid pending application wherein it is pointed out that the converter should hold a measuring container formed from thin, sheet material such as sheet copper, sheet aluminum or the like, a measuring container of this character being exemplified by the container B of the converter A is herein disclosed. With a measuring container B of this character in the converter A and with said measuring container B containing a quantity of liquefied gas as disclosed in my aforesaid pending application, the closure plate 8 of the converter A is disposed on its seat and thus maintained until the evolution of gas increases the pressure interior of said converter A to such an extent that the interior gas pressure holds the closure plate seated and sealed on its seat.

Associated with the converter A is a high pressure valve 15 as known in the art for controlling the flow of gaseous oxygen, said valve 15 being threaded through the converter side wall so as to communicate with the interior of the converter, this valve 15 controlling the passage of high pressure gas to a suitable dispensing conduit 16 which, at its end remote from the converter A, includes a valve 17 and a pressure gauge

18. Further, the converter A may have a second normally closed valve 19 similar to the valve 15 threaded through the wall thereof so as to communicate with the interior thereof, the valve 19 being utilizable as hereinbefore described.

In accordance with the invention, a container or vessel A₁, which serves only incidentally as a converter, is adapted to be associated with the converter A for supplying the latter with liquefied gas. The container A₁ may be substantially a duplicate of the converter A although, preferably and as shown herein, the height of the container A₁ is somewhat less than that of the converter A and, in addition, the container A₁ omits the nozzle 4 and cap 5 of the converter A. Disposed interiorly of the container A₁ and resting upon the plate 14 thereof is a container B₁ which may be substantially a duplicate of the hereinbefore described container B except that it may be somewhat smaller.

Associated with the container A₁ is a valve 20, corresponding with the valve 15, which is threaded through the container side wall so as to communicate with the interior thereof, this valve 20 controlling the passage of gas along a suitable conduit 21 which leads to and is connected to the aforesaid conduit 16. Further, the container A₁ has a second valve 22 similar to the valve 15 threaded through the wall thereof so as to communicate with the interior thereof, the valve 22 being utilizable as hereinbefore described. Still further, the container A₁ has a third valve 23 having a nipple 24 threaded into and through the internally threaded passage of the neck 3, this valve 23 also having a conduit 25 associated therewith. As shown in Fig. 1, the nipple 24 extends upwardly through the plate 14 and through a passage in the bottom of the container B₁, said nipple 24, preferably, forming substantially a liquid-tight seal with the wall surface of said container B₁ which defines said passage. The conduit 25 extends through a passage formed in the wall of the converter A, said conduit 25 being sealed to the wall surface defining said passage and, further, said conduit 25 comprising a downwardly extending end section which opens into the container B of the converter A.

As hereinbefore stated, the converter A is charged with a quantity of liquefied gas L whereupon the converter is sealed. Thereafter, the liquefied gas changes in phase and, after such change of phase has been completed, it results that the converter A is charged with gas at high pressure which, for example, may be of the order of 3,000 pounds per square inch. In accordance with the invention, the converter A is used to charge drums D in succession with gas having a desired high pressure such, for example, as 2,000 pounds per square inch.

To this end, a drum D having its control valve open may be connected to the dispensing end of the conduit 16 whereupon, with the valves 19, 20, 22, 23 closed and with the valve 15 opened, the valve 17 is opened to place the interior of the converter A in communication with the interior of the associated drum D. As a result, the high pressure gas from the converter A is charged into said drum D until the gauge 18 indicates that the desired drum pressure of 2,000 pounds per square inch has been reached. When this operation has been completed, the valve 17 is closed and the associated drum D disconnected from the dispensing end of the conduit 16.

Thereupon, one or more other drums D may

be connected in similar manner and in succession to the dispensing end of the conduit 16 to thereby charge said drums from the converter A in the manner described so that each of them contains gas having the desired pressure of 2,000 pounds per square inch. Eventually, a condition is reached wherein the gas pressure of the converter A, even though relatively high, is less than 2,000 pounds per square inch and hence insufficient to charge a drum D to the desired pressure. When this happens, the drum-charging operation is effected, in accordance with my invention, in the following manner:

Assuming that the closure plate 8 of the container A₁ is removed from its seat and, while the valves 20, 22 and 23 remain closed, a charge of liquefied gas L is obtained in the container B₁ in the manner disclosed, for example, in my aforesaid pending application. Thereupon, the closure plate 8 of the container A₁ is returned to its seat and manually or otherwise held in seated position until the evolution of gas within said container A₁ increases the gas pressure sufficiently to hold said closure plate 8 on its seat. Thereupon, while the valves 17, 19, 22 and 23 remain closed, the valves 15 and 20 are opened. As a result, the gaseous pressure between the converter A and the container A₁ is balanced in response to flow of gas from the converter A to the container A₁ by way of the conduits 16 and 21. As soon as the gas pressure is thus balanced, the valve 23 is opened and, in response to the action of gravity, liquefied gas flows from the container B₁ to the container B by way of the nipple 24, valve 23 and conduit 25. As soon as this action has been completed, the valves 20 and 23 are closed.

The additional supply of liquefied gas which has thus been charged into the container B of the converter A now changes in phase to increase the gas pressure in said converter A to a substantial extent above the desired pressure to which the drums D are to be charged. As soon as this action has been completed, the drum-charging operation is renewed by successively connecting drums D to the dispensing end of the conduit 16 and permitting gas to flow into said drums D in response to opening of the valve 17, the valve 15 remaining opened and the valves 19, 20, 22 and 23 remaining closed during such operation.

Accordingly, in the manner described, additional quantities of liquefied gas L are charged into the container B from the container B₁ as required to thereby maintain the gas pressure in the converter A sufficiently high for drum-charging purposes.

It will be understood that the closure plate 8 of the container A₁ is held on its seat by gas pressure. When this closure plate 8 is to be removed so that liquid material may be disposed within the container B₁, the valve 22 is vented to the atmosphere, a similar venting operation being effected as regards the valve 19 when it becomes desirable to remove the closure plate 8 of the converter A from its seat. Inasmuch as the gas which is charged into the container A₁ serves no useful purpose, in so far as the drum-charging operation is concerned, it will be understood that the converter A₁ should be so designed that the gas space therein is a minimum.

In commercial operation at the present time, drums D which contain gaseous oxygen are charged to a pressure of 2,000 pounds per square inch and, therefore, I have arbitrarily selected

this value as the pressure to which the drums D should be charged. It shall be understood, however, that as regards the various pressures in the converter A and in the drums D, my invention is not to be limited to any particular range of pressures. That is, the converter pressures and the drum pressures may be selected as desired.

Although I have shown the converter A and the container A₁ as of substantially duplicate character, except as regards size, it shall be understood that the invention is not to be thus limited. Obviously, this converter and container need not be of duplicate character and, further, it will be understood that each converter and container unit herein illustrated may be taken as illustrative of banks of converters and containers, the converters and containers of the respective banks being connected in series, if desired. Still further, whether of duplicate character or not, it will be understood that the converters and containers may be any of the practical various forms of containers known in the art as liquefiers for solid carbon dioxide.

After the converter A has been filled with liquefied gas, change in phase of the liquefied gas occurs in response to transfer of heat through the wall of said converter A from the ambient air. If desired, such change in phase may be expedited by exchanging heat in any suitable manner with the liquefied gas.

I have described my invention herein as relating to the charging of the converter A with liquefied gas which is passed thereinto through the filling opening thereof. If desired, said converter A may be a permanently sealed structure serving, in so far as change in phase of liquefied gas is concerned, solely as a converter of that liquefied gas which is received thereinto from the converter or container A₁.

Although I have described my invention in that aspect thereof which involves the charging of drums D from the dispensing conduit 16, it shall be understood that the invention is not to be thus restricted. As well, the gas obtained from the dispensing conduit 16 may be used as desired otherwise than for drum-charging purposes.

While I have described my invention in connection with the passage of liquefied gas into the converter A in order to increase the gas pressure therein, it shall be understood that such gas pressure may be increased in other suitable ways. Thus, for example, a liquid medium may be introduced into said converter A under hydraulic pressure so as to increase the gas pressure there-

in above the lowest charging pressure which has been herein arbitrarily selected as 2,000 pounds per square inch.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. In a gas-dispensing arrangement, a converter having a filling opening, a container interiorly of said converter and spaced from the interior wall surface thereof, said container being adapted to receive a quantity of liquefied gas, a closure plate adapted to be disposed in sealing relation with respect to said filling opening after said container has been charged with liquefied gas, a second converter adapted to be sealed from the atmosphere, a second container interiorly of said second converter and spaced from the interior wall surface thereof, means for equalizing the pressure between said converters, means for passing liquefied gas from said first container to said second container, and a dispensing conduit adapted to be associated with said second converter.

2. In a gas-dispensing arrangement, a converter having a filling opening, a container interiorly of said converter and spaced from the interior wall surface thereof, said container being adapted to receive a quantity of liquefied gas, a closure plate adapted to be disposed in sealing relation with respect to said filling opening after said container has been charged with liquefied gas, a second converter adapted to be sealed from the atmosphere, a second container interiorly of said second converter and spaced from the interior wall surface thereof, said first named converter being disposed at a higher level than said second named converter, means comprising a conduit which connects said converters to equalize the pressure between them, means comprising a conduit for passing liquefied gas from said first container to said second container under the influence of gravity, and a dispensing conduit adapted to be associated with said second converter.

HARRY B. RUDD.
